UNITED STATES PATENT OFFICE.

THOMAS STENHOUSE AND DAVID STENHOUSE, OF WASHINGTON, PENNSYLVANIA, AS
SIGNORS TO HAZEL-ATLAS GLASS CO., OF WHEELING, WEST VIRGINIA, A CORPORA-
TION OF WEST VIRGINIA.

SAFETY MECHANISM.

Application filed August 29, 1923. Serial No. 660,057.

To all whom it may concern:

Be it known that we, THOMAS STENHOUSE and DAVID STENHOUSE, citizens of the United States, residing at Washington, in the county of Washington and State of Pennsylvania, have invented a new and useful Safety Mechanism, of which the following is a full, clear, and exact description.

Our invention relates to a safety mechanism to be used with a machine employing in its operation two different kinds of power, such as compressed air and electricity, and its object is to provide a means whereby the electrical-control mechanism is rendered inoperative, and held in inoperative position whenever, for any reason, the air supply is shut off.

In many types of glass pressing and blowing machines, for use with which this invention is more particularly designed, a series of molds mounted on a rotating table are moved successively to a station beneath a plunger which is projected into and withdrawn from each mold by compressed air, while that particular mold remains at its station beneath the plunger. The step by step movement for successively moving the molds to the operating station is imparted to the carrier table by an electrically driven apparatus.

When for any reason the air supply fails, or is shut off for repairs to the machine or pressure system, the plunger or other fluid controlled parts may move or be moved from their normal positions so as to destroy the synchronized movements of the machine and bring these parts into the paths of movement of the molds or other electrically-operated parts. If, under these conditions, the electrically-controlled means should be operated, or should continue to operate, breakage of parts would occur and the machine be entirely disorganized.

The present invention provides an interlocking control between the air and electrical systems whereby the electric controller is moved to inoperative position or held in inoperative position whenever, for any reason whatever, the air supply is cut off. Thus it becomes impossible to operate the electrically-controlled part of the apparatus unless the entire mechanism is in proper working condition, and the possibility of

breakage and disorganization of the parts is eliminated.

The objects and advantages of this invention will be more clearly understood from the accompanying drawings showing one embodiment of the invention, in which:

Figure 1 is a side elevation, partly in section, of a portion of a glass machine, showing our invention applied thereto.

Figure 2 is a fragmentary plan view of a portion of the machine and air lines.

Figure 3 is an enlarged side elevation of a circuit breaker with the safety air cylinder shown in section.

Figures 4 and 5 are side and front elevations, respectively, on a somewhat enlarged scale, of the switch box and safety air cylinder, and

Figure 6 is a section similar to Fig. 3 through the safety air cylinder, but showing the same in conjunction with a switch arm.

It may be here stated that the particular construction of the machine itself forms no part of the present invention; therefore, in Figs. 1 and 2 of the drawings the main portions of the machine are indicated in relatively light lines, in order to more clearly distinguish the same from the safety attachment which is indicated by comparatively heavy lines.

Referring to the drawings more in detail, the numeral 1 indicates generally the glass machine, which includes a rotatable table 2 on which are mounted a plurality of sets of molds 3. A step by step rotary motion, for moving the molds successively into operating position, is imparted to table 2 by a Geneva wheel 4, which is continuously rotated by an electric motor 5 in the electric circuit 6; and a typical variable speed switch box 7 provided with operating handle 8 is also placed in the circuit for controlling the motor.

In glass machines of the pressing and blowing type a plunger is provided for producing the initial opening in the glass blank or parison. Such a plunger is indicated by reference numeral 9 in Fig. 1 and is operated by fluid pressure through the medium of the cylinder 10 and piston 11. This plunger is adapted to be projected into the molds 3 successively when the table is held stationary by means of the Geneva wheel 4.

As more clearly shown in Fig. 2 of the drawings, a main air line 12 is employed to supply a series of glass machines, and a branch line 13, in which is mounted a shut-off valve 14', leads from the main line 12 to each machine of the series. From the branch line 13 pipes 14 may lead to the plunger-operating cylinder, blowhead, mold clamps, conveyors and other elements intended to be operated by fluid pressure.

Interposed between the shut-off valve 14' and the conduits leading therefrom to the various mechanisms is an additional conduit 15 which normally supplies fluid under pressure to the cylinder 16 which forms a substantial part of the safety mechanism. Slidably mounted in the cylinder 16 is a piston 17 carried on the piston rod 18, and this piston is normally forced in the direction of the switch arm 8 by means of compression spring 19 which surrounds one end of the piston rod and is confined between the piston 17 and the adjacent end of the cylinder 16. A plate 20 is secured to the outer end of the piston rod 18 for direct engagement with the switch arm 8. By referring to Figs. 4 and 6 it will be seen that the fluid-pressure conduit 15 opens into the end of the cylinder 16 opposite to that in which the spring 19 is located, thereby providing means for moving the piston against the pressure of spring 19.

In the operation of the safety mechanism the piston 17 and likewise the rod 18 and plate 20 are maintained in the positions shown in Figs. 4 and 6 so long as the glass machine is working under normal conditions. Should the air supply fail, or should the machine be shut down for any purpose by closing the valve 14' the pressure will be removed from the left hand side of piston 17 (Fig. 6) and the spring 19 will move the piston over to the dotted line position, thereby causing the plate 20 to engage the switch arm 8 and open the circuit to the motor 5. If now the operator desires to start up the machine he is prevented from doing so until the air is turned on. This is due to the fact that the plate 20 is held against the switch arm 8 by means of the spring 19, and consequently locks the same against movement. It should be here noted, however, that so long as the air pressure is on the machine the piston 17 will be held retracted and the switch arm 8 will be free for movement to either open or closed position.

In Fig. 3 we have shown a somewhat modified arrangement of the safety mechanism in which the cylinder 30 is attached to a circuit-breaker casing 31. In this instance the piston rod 32 carries a roller 33 adapted for co-operation with a lever 34 which is pivotally mounted on the circuit-breaker casing, as indicated at 35. This form of the invention is otherwise identical with that

previously described and a detailed description thereof is believed unnecessary.

As previously stated herein, considerable damage will be caused in the event that the electrical apparatus is set in motion while the air is turned off or if, for any other reason, the air fails to reach the parts to be operated thereby. This may be exemplified in the case of the plunger which intermittently descends into the molds when the table is held stationary. This plunger may be in a mold when the machine is shut down, or, due to escaping air, the plunger may be lowered into a mold or between two molds. With the present arrangement of safety mechanism, however, such abnormal positions of the air-operated parts are avoided, and consequently it will be apparent that all danger of such accidents and wrecking of the parts is completely eliminated.

Having fully described our invention, what we claim as new and desire to secure by Letters Patent is:

1. The combination with a machine comprising parts operated from one source of power, other parts co-operating therewith and operated from another source of power, of means rendering inoperative the first-mentioned source of power by the shutting off of the second-mentioned source of power.

2. The combination with a machine operated partly by fluid pressure and partly by electricity, of means to prevent closing of the electric circuit while the fluid pressure is turned off.

3. The combination with a machine operated partly by fluid pressure and partly by electricity, of automatic means for opening the electric circuit when the fluid pressure is turned off.

4. The combination with a machine operated partly by electricity and partly by fluid pressure, of means rendering the electric operation inoperative by shutting off the fluid pressure.

5. The combination with a machine operated partly by fluid pressure and partly by electricity, a switch normally operable to control the electric circuit, and means for automatically locking said switch in open position when the fluid pressure is turned off.

6. The combination with a machine comprising a movable table, a plurality of molds carried thereby, a source of power for operating said table, a plunger adapted to successively enter said molds, and means for operating said plunger, of means for rendering inoperative said source of power by the shutting off of the plunger-operating means.

7. The combination with a machine comprising a rotatable table, a plurality of molds carried thereby, a source of power for operating said table, a plunger adapted

to successively enter said molds, and means for operating said plunger, of means for rendering inoperative said source of power by the shutting off of the plunger-operating means.

8. The combination with a machine having an electrically-operated table, a plurality of molds thereon, a fluid-operated plunger adapted to successively enter said molds, of means for preventing the closing of the electric circuit while the fluid pressure is shut off.

9. The combination with a machine including a rotatable table, molds mounted thereon, a Geneva wheel geared to said table, an electric motor for operating said Geneva wheel, a fluid-operated plunger adapted to successively enter said molds, and automatic means for opening the circuit to said motor when the fluid pressure is shut off, said means being adapted to prevent the closing of said circuit until the fluid pressure is turned on.

10. The combination with a machine operated partly by fluid pressure and partly by electricity, of means for automatically opening the electric circuit when the fluid pressure is shut off, said means including a cylinder and piston, a spring engaging one side of the piston, and a fluid pressure con-

duit leading to the opposite side of the piston.

11. In combination with a machine operated partly by fluid pressure and partly by electricity, a switch for controlling the electric circuit, a cylinder mounted adjacent said switch, a piston and piston rod in said cylinder, a spring engaging one side of said piston, and a fluid pressure conduit leading to the other side of said piston, whereby the piston rod will engage and open said switch when the fluid pressure is turned off.

12. The combination with a machine having a rotatable table, an electric motor for operating said table, a plurality of pressure-operated elements co-operating with said table, a main fluid pressure line, a branch line leading to said machine, a plurality of conduits leading from the branch line to the various fluid-operated elements, a shut-off valve in the branch line, an additional fluid-pressure conduit leading from said branch line just beyond the valve, and means connected with said additional fluid-pressure conduit for preventing operation of said table when the fluid pressure is turned off.

THOMAS STENHOUSE.
DAVID STENHOUSE.

to successively enter said molds, and means for operating said plunger, of means for rendering inoperative said source of power by the shutting off of the plunger-operating means.

8. The combination with a machine having an electrically-operated table, a plurality of molds thereon, a fluid-operated plunger adapted to successively enter said molds, of means for preventing the closing of the electric circuit while the fluid pressure is shut off.

9. The combination with a machine including a rotatable table, molds mounted thereon, a Geneva wheel geared to said table, an electric motor for operating said Geneva wheel, a fluid-operated plunger adapted to successively enter said molds, and automatic means for opening the circuit to said motor when the fluid pressure is shut off, said means being adapted to prevent the closing of said circuit until the fluid pressure is turned on.

10. The combination with a machine operated partly by fluid pressure and partly by electricity, of means for automatically opening the electric circuit when the fluid pressure is shut off, said means including a cylinder and piston, a spring engaging one side of the piston, and a fluid pressure con-

duit leading to the opposite side of the piston.

11. In combination with a machine operated partly by fluid pressure and partly by electricity, a switch for controlling the electric circuit, a cylinder mounted adjacent said switch, a piston and piston rod in said cylinder, a spring engaging one side of said piston, and a fluid pressure conduit leading to the other side of said piston, whereby the piston rod will engage and open said switch when the fluid pressure is turned off.

12. The combination with a machine having a rotatable table, an electric motor for operating said table, a plurality of pressure-operated elements co-operating with said table, a main fluid pressure line, a branch line leading to said machine, a plurality of conduits leading from the branch line to the various fluid-operated elements, a shut-off valve in the branch line, an additional fluid-pressure conduit leading from said branch line just beyond the valve, and means connected with said additional fluid-pressure conduit for preventing operation of said table when the fluid pressure is turned off.
